UNITED STATES PATENT OFFICE.

FRANK P. WEST, OF PORT ORCHARD, WASHINGTON.

CURTAIN-HOLDER.

1,072,063.

Specification of Letters Patent.

Patented Sept. 2, 1913.

Application filed November 25, 1912. Serial No. 733,492.

To all whom it may concern:

Be it known that I, FRANK P. WEST, a citizen of the United States, residing at Port Orchard, in the county of Kitsap and 5 State of Washington, have invented certain new and useful Improvements in Curtain-Holders, of which the following is a specification.

This invention relates to curtain poles, 10 more particularly to devices of this character employed for supporting lace curtains and similar hangings, and has for one of its objects to provide a simply constructed device whereby a lace curtain may be quickly 15 suspended and without the necessity for forming hems on the curtain or employing pins or other similar fastening devices to connect the curtain to the pole.

Another object of the invention is to provide 20 a simply constructed device whereby any surplus length of the curtain may be "taken up" and disposed within the supporting member.

Another object of the invention is to provide 25 a simply constructed device whereby the length of the curtain may be readily adjusted without severing any portion thereof.

With these and other objects in view the invention consists in certain novel features 30 of construction as hereinafter shown and described and then specifically pointed out in the claims, and in the drawings illustrative of the preferred embodiment of the invention.

35 Figure 1 is a front elevation of a portion of a window including the casing and frame with the improvement attached and in front elevation. Fig. 2 is a plan view of the parts shown in Fig. 1. Fig. 3 is an enlarged longitudinal section on the line 3—3 of Fig. 2. Fig. 4 is an enlarged transverse section on the line 4—4 of Fig. 3 looking in the direction of the arrow with the slots of the telescoping cylinders disposed in registering relations. Fig. 5 is a transverse section on the line 5—5 of Fig. 1 looking in the direction of the arrow. Fig. 6 is a view similar to Fig. 4 showing the relative position of the parts after the curtain has been connected 50 therewith.

Corresponding and like parts are referred

to in the following description and indicated in all the views of the drawings by the same reference characters.

The improved device may be constructed 55 of any suitable material and any suitable length and size and adapted to curtains of various sizes, and comprises an outer cylindrical member 10 and an inner cylindrical member 11, the inner cylinder being somewhat smaller than the outer cylinder whereby a space is left between the cylinders, as indicated at 12. The outer cylinder 10 is closed at one end, preferably by means of a head 13 having a shoulder 14 to form a bearing for the adjacent terminal of the inner cylinder 11. The inner cylinder 11 is provided at the end opposite to the filler member 13 with a filler 15 preferably of wood and enlarged to rotatably engage against 60 the inner face of the outer cylinder 10, as shown. The outer cylinder 10 is provided with a longitudinal slot 16 while the inner cylinder 11 is provided with a similar longitudinal slot 17, the two slots registering 65 when the inner cylinder is adjusted to one position.

Fitting over the open end of the outer cylinder 10 is a cap 18 having a closure 19, preferably of wood, at its outer end. The 80 cap 18 is rotatable over the outer cylinder 10 and is spaced a distance from its open end, as shown. A stud 20 is connected to the closure 13 of the outer cylinder and is provided with a flat bearing 21 externally 85 of the closure 13, while a similar stud 22 projects from the closure 15 of the inner cylinder. The stud 22 extends through the closure 19 of the cap and is provided externally of the cap with a flat bearing 23. A 90 coiled spring 24 surrounds the stud 22 between the closure members 15 and 19 and is connected at one end at 25 to the closure 15 and at the other end at 26 to the closure 19. By this means the spring operates to maintain 95 the inner cylinder yieldably in a certain predetermined position relative to the outer cylinder, as hereafter explained.

Connected to the outer cylinder 10 are bearing plates 27, preferably located at opposite sides of the cylinder, and extending over the cap 18 and secured thereto by

screws or other similar fastening devices 28. The window casing is provided with brackets 29 each having a slot 30 to receive the bearings 21—23 and hold them from rotation.

With a device thus constructed the operation is as follows: The roller as a whole is removed from the brackets 29 and the screws 28 detached and the cap 18 together with its head 19 rotated upon the cylinder 10 and upon the stud 22 until the slots 16—17 are opposite each other. The curtain material is then thrust through the registering slots until a sufficient quantity has been inserted 15 into the inner cylinder 11 to bring the lower edge of the curtain at the proper distance from the floor. The cap 18 together with its head 19 is then rotated once or more against the resistance of the spring 24 or 20 until the slot 17 has been disposed at the opposite side of the cylinder 10 from the slot 16, or even to a greater extent, this movement causing a certain portion of the curtain material to be rolled around between 25 the two cylinders and thus firmly lock the curtain material to the cylinders. By rotating the inner cylinder one or more revolutions the locking action will be correspondingly increased and the "grip" of the 30 curtain upon the rollers likewise increased to prevent its removal therefrom when the roller is disposed in the brackets. When the inner roller 11 has been rotated to a sufficient distance to firmly lock the curtain material 35 in position the screws 28 are again inserted to hold the cap and the inner cylinder in its adjusted position. The roller is then elevated and the bearings 21—23 deposited respectively in the slots 30 of the hangers. By 40 this means the curtain is suspended from the roller and retained in position. If preferred the curtain material may be wrapped one or more times around the outer cylinder to conceal the same.

45 The improved device is simple in construction, can be inexpensively manufactured and of any required length or size.

The bodies of the cylinders 10—11 and of the cap 18 will preferably be of sheet metal 50 while the terminals 13—15—19 will preferably be of wood, but may be of other material if preferred.

Having thus described the invention, what I claim is:

55 1. A curtain pole comprising an outer cylindrical member having a longitudinal slot, an inner cylindrical member having a longitudinal slot, said slots adapted to receive curtain material, means for rotating the inner cylindrical member within the outer cylindrical member, and means for locking the inner cylindrical member in its adjusted position.

60 2. A curtain pole comprising an outer cylindrical member having a longitudinal slot,

an inner cylindrical member having a longitudinal slot, said slots adapted to receive curtain material, a cap mounted for rotation upon the outer cylindrical member, a spring connected respectively to the inner 70 cylindrical member and to the cap, bearing studs carried respectively by said outer cylindrical member and the cap, means for locking said cap to said outer cylindrical member and brackets for supporting said 75 bearings and adapted to be connected to a window.

3. A curtain pole comprising an outer cylindrical member having a longitudinal slot and open at one end and with a head closing the other end and provided with an inwardly directed annular shoulder, an inner cylindrical member having a longitudinal slot and rotatably engaging the annular shoulder at one end and with a head closing 80 the other end, said head having an outwardly directed flange rotatably engaging in the outer cylindrical member and said slots adapted to receive curtain material, means for rotating the inner cylindrical member within the outer cylindrical member, and means for locking the inner cylindrical member in its adjusted position.

4. A curtain pole comprising an outer cylindrical member having a longitudinal slot 95 and open at one end and with a head closing the other end and provided with an inwardly directed annular shoulder, an inner cylindrical member having a longitudinal slot and rotatably engaging the annular 100 shoulder at one end and with a head closing the other end, said head having an outwardly directed flange rotatably engaging in the outer cylindrical member and said slots adapted to receive curtain material, a 105 cap mounted for rotation upon the outer cylindrical member, a stud extending from the closure of the outer cylindrical member, a stud extending from the closure of the inner cylindrical member and through the cap, a 110 spring connected respectively to said cap and inner cylindrical member and yieldably coupling the inner cylindrical member and the cap, means for locking said cap to said outer cylindrical member, and brackets 115 adapted to be attached to supporting means and receiving said studs and holding the same from turning.

5. A curtain pole comprising an outer cylindrical member having a longitudinal slot, 120 an inner cylindrical member having a longitudinal slot and rotatably disposed within the outer cylindrical member, a cap engaging over the outer cylindrical member, means for yieldably coupling the cap to the inner 125 cylindrical member, and means for locking the cap to the outer cylindrical member.

6. A curtain pole comprising an outer cylindrical member having a longitudinal slot, 130 an inner cylindrical member having a lon-

itudinal slot and rotatably disposed within the outer cylindrical member, a cap engaging over the outer cylindrical member, studs extending respectively from said outer cylindrical member and from said cap, brackets adapted to be connected to a stationary supporting means and receiving said studs and holding the same from turning, and

means for yieldably coupling the cap to the outer cylindrical member. 10

In testimony whereof I affix my signature in presence of two witnesses.
